UNITED STATES PATENT OFFICE.

CRAWFORD WILLIAM HUME, OF GLASGOW, SCOTLAND, ASSIGNOR TO JAMES HOWDEN & COMPANY LIMITED, OF GLASGOW, SCOTLAND, A CORPORATION OF THE UNITED KINGDOM OF GREAT BRITAIN AND IRELAND.

FURNACE FRONT.

1,402,362.

Specification of Letters Patent. Patented Jan. 3, 1922.

Application filed May 5, 1921. Serial No. 466,949.

To all whom it may concern:

Be it known that I, CRAWFORD WILLIAM HUME, a subject of the King of the United Kingdom of Great Britain and Ireland, and 5 residing at Glasgow, Scotland, have invented a certain new and useful Improvement in Furnace Fronts, of which the following is a specification.

This invention relates to furnace fronts of 10 the type adapted for oil burning or solid fuel burning, and comprising a front plate and a back plate between which are formed valve-controlled lateral air openings, a deflector adapted to direct the air entering the 15 lateral openings toward the furnace, and an oil burner passing through the deflector and arranged substantially centrally of the stream of air directed thereby.

The invention is illustrated by way of 20 example in the accompanying drawing in which Fig. 1 is a vertical section, Fig. 2 a horizontal section, Fig. 3 a section at right angles to Fig. 1, and Fig. 4 an elevation.

The improved furnace front shown 25 comprises a front plate 1 and a back plate 2 and a lateral wall 3' connecting said plates and having valve-controlled lateral air openings 3. Installed between the plates 1, 2 is a deflector 4 adapted to direct the air entering the lateral openings 3 towards the furnace, and passing through the deflector is an oil burner 5 which is arranged substantially 30 centrally of the stream of air directed by the deflector.

For controlling the lateral openings 3 there are provided butterfly valves 6 which are adapted to swing on vertical axes and

are interconnected by cranks 8 and a connecting rod 9. One valve is fitted with a bevel wheel 10 meshing with a mutilated 40 bevel wheel 11' rotatable by a handle 11 whereby the valves may be operated in unison.

The deflector is constituted by contiguous curved plates which are dished in their 45 mid-portions at 12 to accommodate the oil burner 5.

If desired, the valves may be separately operable.

13 denotes a door facilitating removal of 50 carbon from the furnace.

I claim:—

A furnace front comprising a front plate, a back plate, a cylindrical lateral wall connecting said plates and formed with two 55 diametrically opposite air openings, two connected valves controlling said openings, said valves being mounted to swing on vertical axes, a deflector comprising two contiguous curved plates dished in their mid-portions, the abutting faces of said plates being in a vertical plane, said deflector being adapted to direct air entering said openings, and an oil burner supported by said front plate and passing between the dished 60 mid-portions of said deflector. 65

In testimony whereof I have signed my name to this specification in the presence of two subscribing witnesses.

CRAWFORD WILLIAM HUME.

Witnesses:

ISABEL ROLLO,
FLORENCE HOUSTON.
